ELASTIC YARN

Wilbert D. Smith, Philadelphia, Pa.

Application December 21, 1939, Serial No. 310,434

2 Claims. (CL 57—139)

This invention relates to elastic yarns of the type which includes a continuous strand or thread of cut or extruded rubber (latex) and at least one inelastic thread, i. e., a thread composed of intertwined natural vegetable or animal fibres such as cotton, flax, wool, etc., or wherein the inelastic thread is in the form of a continuous filament or strand of synthetic material, such as Rayon, Nylon, etc., or formed of short pieces thereof spun together alone or intermixed and twisted with natural animal or vegetable fibres to form the thread.

Usually elastic composite yarns are constructed with two of the so-called inelastic threads wound in opposite directions, in successive layers respectively, around the elastic strand or core thread, while such core thread is maintained in a strictly rectilinear state, to form a covering for the latter. Such covered rubber yarns are commonly referred to as lastex.

Covered rubber yarns have many well-known faults and inadequacies, such as relative slippage between the covering thread or threads and the rubber core, in use or when the composite yarn is being knitted, woven or braided into a fabric, with frequent breakage of one or the other of the component elements of the yarn under tensile strains.

When a fabric containing covered rubber yarn is cut, or when the covered rubber yarn is cut or the rubber breaks at any point throughout the length of the composite yarn, the rubber core thread, which is normally under a tension, retracts for quite a distance from the point of cut into the tube-like outer covering composed of the inelastic thread or threads.

In other instances the covering has been composed of a roving formed of animal or vegetable fibres and having substantially no twist, with a view toward producing maximum coverage of the rubber core. Due to the relative looseness of the fibres of such coverings, a large amount of lint is collected at the guide eyes through which the composite yarn passes in being fed to the needles of a knitting machine, or in being drawn from a shuttle in weaving, etc., during incorporation of the covered rubber yarn in a fabric, resulting in breakage of the yarn.

Due to the fact that during the production of covered rubber yarns, as known to the prior art, the covering thread is laid in closely adjacent convolutions around the rubber core, in many instances with a second covering thread correspondingly laid around the initial covering in a direction opposite to the laying of the initial cov-

ering, speed of production is relatively slow and the yardage per pound relatively low.

One object of the present invention is to provide a composite elastic yarn which will eliminate relative slippage between the threads and the retraction of the rubber strand relative to the inelastic component of the yarn when the yarn is cut.

Another object of the invention is to construct the composite yarn in such a manner that the speed of production will be materially increased, for example, in excess of 50% over and above maximum production under the prior art methods.

Another object of the invention is to construct the composite yarn in such a manner that the yardage per pound will be increased substantially 25%.

In producing a composite yarn under the principles of the present invention, an inelastic thread of predetermined count, diameter, or cross-sectional area, is interspun or intertwined with a continuous strand of rubber, either cut or extruded and of the same or larger or smaller cross sectional area than the inelastic thread, in such a manner that the ultimate composite yarn is formed of closely axially compacted interlocking alternating convolutions of the two threads. The inelastic thread has in it an initial twist of a predetermined number of turns per inch in one direction, and the rubber thread is given an initial twist of a predetermined number of turns per inch in the direction opposite to the twist of the inelastic thread. The two threads are intertwined or interspun in a direction consistent with that of the initial twist of the inelastic thread and the intertwining of the two threads together is effected at a predetermined number of turns per inch.

In the accompanying drawing :

Fig. 1 diagrammatically illustrates a piece of the inelastic yarn, shown as having an initial twist in one direction throughout its length;

Fig. 2 illustrates a piece of the rubber thread, with an initial twist in a direction opposite to that of the inelastic thread;

Fig. 3 illustrates the two threads interspun or intertwined together in a direction consistent with the twist of the inelastic thread;

Fig. 4 is a view similar to Fig. 3 illustrating two inelastic threads intertwined with a single strand of rubber; and

Fig. 5 diagrammatically illustrates an apparatus for producing composite elastic yarns in ac-

cordance with the principles of the present invention.

As shown in Fig. 5, a naked rubber thread A is first wound on the core 1 of a spool 2, between the end flanges 3 and 4 thereof, without any twist whatsoever being put in the rubber strand A. The spool 2 is mounted on and revolves about a vertically disposed stationary spindle 5, at a pre-determined speed, for example about 6000 R. P. M. The rotation of the spool 2, is effected by any suitable means, such as a pulley 6 loosely mounted on the spindle 5 and a belt 7 connecting the pulley 6 with a suitable source of rotary motion.

Lying on top of the flange 4 of the spool 2 is a central disc 8. From the disc 8 extends a light arm, such as a wire 9. The arm 9 is provided, adjacent its outer end, with an eye or flyer 10 through which the rubber strand A passes from the spool 2 to the bore of a tubular spindle 11 which is mounted above the spindle 5, in axial alignment therewith.

The hollow spindle 11 is secured in any suitable kind of rigid support 12 against rotation. Rotatably mounted on the hollow spindle 11 is a pulley 13 which is driven by a belt 14, from any suitable source of power, in a direction opposite to the direction of rotation of the spool 2 on the spindle 5 at a speed of about 8000 to 12,000 R. P. M. Carried by the pulley 14 is a spool 15 upon which is wound the inelastic thread B, said thread having an initial twist of a predetermined number of turns per inch, as illustrated in Fig. 1. The bulk of the inelastic yarn B is wound on the core 16 of the spool 15 between the end flanges 17 and 18 thereof.

Resting on the upper flange 18 of the spool 15 is a central disc 19 which is provided with an arm 20 having an eye or flyer 21 adjacent its outer end through which the inelastic yarn B passes, at an angle to the thread A, from the spool 15 to a point X above the upper end 22 of the hollow spindle 11. At the point X the converging threads A and B meet and are intertwined with each other.

As a matter of illustration, the spool 2 is rotated in a clock-wise direction, as viewed from above, which puts a right-hand twist in the rubber A, as illustrated in Fig. 2. Before being wound on the spool 15, the thread B, in the course of its manufacture, has been given a left-hand twist, as illustrated in Fig. 1, and because thereof the spool 15 is rotated in a counter-clockwise direction, as viewed from above, or, in other words, in a direction opposite to the direction of rotation of the spool 2 and consistent with the initial twist of the inelastic thread B.

The right-hand twist of the elastic rubber thread A meeting the left-hand twist of the inelastic fibrous thread B, at the point X, with the spool 15 traveling in a counter-clockwise direction, causes the two converging threads A and B to intertwist together in the manner illustrated in Fig. 3, i. e., with alternating convolutions of the respective threads A and B closely compacted axially of the composite yarn C with the convolutions being of the left-hand variety.

The right-hand twist of the rubber A reacting against the left-hand twist of the inelastic thread B, during the left-hand twisting of the two together, causes the convolutions *a* and *b* of the rubber thread A and inelastic thread B to interlock with each other and in so doing prevent the composite yarn C produced thereby from kinking in future use. Obviously the directions of twist and intertwist, above described, may be

reversed and the speed of rotation of the two spools 2 and 15 varied as desired, without departing from the present invention.

On each of the spindles 5 and 11, above and bearing upon the central discs 8 and 19 respectively, are weights 23 and 24 respectively. These weights tend to retain the discs 8 and 19 in frictional contact with the flanges 4 and 18 respectively of the spools 2 and 15, to insure rotation of the arms 9 and 20 and their respective flyers with the spools 2 and 15 respectively, while providing for restricted or retarded relative rotation between said discs and said spools. In the case of the rubber strand A the weights 23, of which there may be one or more, and which are interchangeable or applied in units to produce the particular weight desired to place more or less restriction upon the relative rotation between the eye or flyer 10 and spool 2, controls the tension on the rubber strand A as it is drawn from the spool by winding of the composite yarn C on the ultimate reel or cone.

The winding of the finished composite yarn C may be accomplished by any of the well-known devices employed for this purpose in the art.

The number of rotations per minute of the spool 2 and flyer 10 and the speed of take up of the finished yarn C from the point X, which may be at the rate of 75 to 85 inches per minute, for example, determines the extent of twist put into the rubber A, which, for practical purposes, with a rubber of normally .008 inch in diameter for example, may be approximately 6 to 12 turns per inch. Thus, the degree of extensibility of the rubber A going into the composite yarn C is rather accurately controlled, it being noted that at the point X intertwisting of the threads A and B together, the rubber A is under tension and in a stretched condition to a predetermined degree.

In a like manner the inelastic thread B is retained at a certain amount of tension when the intertwisting thereof with the rubber thread A takes place at the point X, and this is controlled by the amount of weight 24 placed on the spindle 11 above the disc 19, so that the relative rotation between the eye or flyer 21 and the spool 15 may be accurately controlled.

If desired, a second inelastic thread, shown at D in Fig. 4, may be twisted with the threads A and B at the point X, as by running two ends from a single spool 15 through the flyer 21 or from separate spools superimposed upon each other on the spindle 11, with both threads running concurrently to and through the flyer 21.

As a result of the above operations and as shown in Figs. 3 and 4, the composite yarn C is made up of rather tightly interlocking alternating convolutions *a* and *b* of the threads A and B respectively, and as a result of such relatively tight intertwisting the inelastic thread can not slip relative to the elastic thread, regardless of the number of times the composite yarn may be stretched and permitted to retract. The expansion and contraction of the components A and B of the composite yarn C react coordinately. The inelastic thread B governs the maximum stretch of the composite yarn C, but even when stretched to a maximum the intertwisting of the two threads together is maintained, although the pitch of the convolutions *a* and *b* be materially lengthened during such stretching. However, as the composite yarn C is permitted to retract to normalcy, the pitch of the convolutions is reduced accordingly until said convolu-

tions again become closely compacted one with the other axially of the yarn C, as shown in Fig. 3. With this arrangement, the inelastic thread in the composite yarn tends to hide or at least detract from the prominence of the intertwisted rubber thread A, so that in a fabric knitted, woven, or braided, in which the composite yarn C is incorporated, the rubber is relatively obscure and the fibrous inelastic thread is relatively prominent. This may be further accentuated by the character of the inelastic thread B employed. For example, the smaller the initial twist in the inelastic thread B the greater the rubber obscuring qualities thereof. Likewise, variations in diameters between the elastic yarn and the inelastic yarn may be utilized to increase the relative obscurity of the rubber with respect to the inelastic thread in the finished composite yarn and the fabric in which such yarn is incorporated.

I claim:

1. A composite yarn comprising an elastic thread and an inelastic thread respectively formed into successive convolutions alternately intertwined with each other in closely compacted relation axially of said yarn with the elastic thread having an initial twist in a direction opposite to that of the intertwisting of said two threads together. 5

2. A composite yarn comprising an elastic 10 thread and an inelastic thread respectively formed into successive convolutions alternately intertwined with each other in closely compacted relation axially of said yarn with the elastic thread having an initial twist in a direction opposite to that of the intertwisting of said two threads together and with the inelastic thread 15 having an initial twist in a direction consistent with that of said intertwisting.
